PICKLING BASKET

Stephen L. Williams, Bridgeport, Ohio, assignor to
 Extruded Metal Products Company, Bridgeport,
 Ohio, a corporation of Ohio

Application April 6, 1934, Serial No. 719,277

6 Claims. (Cl. 266—7)

This invention relates broadly to pickling baskets, and more particularly to a basket for retaining small stampings, forging and like articles while the same are subjected to immersion 5 in the fluid of the pickling bath.

The object of the invention is to provide a basket having a bottom which may be dropped downwardly about a pivotal connection for permitting the retained articles to drop by gravity out of the 10 basket for unloading the latter.

Another object of the invention is to provide novel means for locking the bottom in normally closed position and for unlocking the same to allow the basket to be automatically emptied.

15 In describing the invention in detail, reference is herein had to the accompanying drawings in which—

Figure 1 is a top plan view of the invention;

Figure 2 is a vertical sectional view taken on line 2—2, Fig. 1, showing one of the hinged bottom sections in its open or unloading position;

Figure 3 is an enlarged sectional view taken on line 3—3, Fig. 1, illustrating the manner of operating the locking shafts; and—

25 Figure 4 is a detail view of a locking shaft illustrating the construction thereof.

Referring to said drawings, the reference numeral 1 designates a substantially rectangular base frame consisting of spaced parallel end members and side members, and also having an integral transverse member 2 located midway between the end members and connecting the two longitudinal side members.

Rising vertically from the base 1 are the side 35 walls 3 and end walls 4 of the basket, said walls being supported by means of corner posts 7, as shown in Fig. 2, the lower ends of the corner posts 7 being threadedly received in the base 1. Each side wall and end wall has a plurality of grille-like openings 6 thereby to afford free and ready 40 access of the pickling fluid to the interior of the basket when the latter is immersed in the bath. Eyes 5 are provided at the upper end of each corner post 7 for receiving hooks of a lifting crane or 45 pickling apparatus.

The bottom of the basket consists of two sections 8 and 9, each being pivotally connected to the base frame 1 at its outer edge by a hinge connection 10. The confronting free inner edges of 50 the bottom sections (which latter also have the grille-like openings) are maintained in normal horizontal closed position by means of manually rotatable locking shafts 12.

Each locking shaft 12, as shown in detail in Fig. 55 4, consists of a length of shaft whose length ex-

ceeds the width of the basket, as shown in Fig. 1. At spaced distances throughout the extent of the shaft are recesses or cut-out portions 13, the shaft at the location of each of the recesses having a segmental contour in cross section.

In assembled relation, the recesses 13 are designed to register with spaced forwardly projecting lugs 14 formed integral with the inner edge of each bottom section 8 and 9 so that, when the locking shafts 12 are in the position shown in Fig. 1, and at the left of Figs. 2 and 3, the segmental portions of the shafts will occupy underlying supporting relation to the lugs, thereby maintaining and locking the sections 8 and 9 closed to form a fixed bottom for the basket. When, however, following removal of the basket from the pickling bath, a locking shaft 12 is manually rotated by means of one of the hand levers 15 to the extent of 90° of a circle, as shown at the right of Figs. 2 and 3, the shaft is brought out of underlying contact with the lugs 14 by reason of the provision of the recesses, thus permitting the respective bottom section supported to drop to a depending vertical position about its hinge connection 10 for dumping the contents outwardly and downwardly 25 through the bottom.

A plurality of bearings 16 are provided on each side of the transverse member 2 of the base, in which bearings the locking shafts 12 are journaled. One such bearing is provided intermediate two 30 recesses of the shaft to afford strength and rigidity to the structure.

Stops 17 are located on the base 1 for limiting the rotation of the levers 15.

What is claimed is—

1. In a pickling device, a base having an intermediate transverse member, a basket carried by the base, a pair of bottom sections for the basket pivoted at their outer ends to the base and having their inner ends free and confronting the transverse member, bearings carried by the transverse member and extending outwardly beyond the opposite sides thereof, a pair of rotatable shafts disposed on opposite sides of the transverse member and journaled in the adjacent bearings, spaced projections on the inner ends of the bottom sections, the shafts having segmental cut-outs to register with the projections in one position of the shafts and in a second position to be out of register with the shafts so that the projections seat upon the shafts, hand levers at one end of the shafts for operating the same, and stop means to engage and hold the levers against downward movement in said second positions of the shafts while permitting upward 55

- movement of the shafts to said first position to release the bottom sections for downward movement.
2. In a pickling device, a pickling basket having a pivoted bottom member with a free end provided with spaced outwardly extending prolongations, a shaft vertically alined with and underlying and engaging the prolongations in closed position of the bottom member to support the latter against downward movement in one position of the shaft and having cut-outs which in a second position of the shaft register with the prolongations to allow the bottom member to move downwardly, a hand lever connected to the shaft for rotating same, and a rigid stop member for engaging the lever to hold the latter in substantially horizontal position when the shaft is in its said first position.
3. In a pickling device, a pickling basket having a pivoted bottom member with a free end provided with spaced outwardly extending prolongations, a shaft vertically alined with and underlying and engaging the prolongations in closed position of the bottom member to support the latter against downward movement in one position of the shaft and having cut-outs which in a second position of the shaft register with the prolongations to allow the bottom member to move downwardly, a hand lever connected to the shaft for rotating same, and means engageable with the lever to hold the shaft against movement in said first named position thereof while permitting movement of the lever to cause the shaft to assume its said second position.
4. In a pickling device, a pickling basket having a pivoted bottom element with a free end, a rotary element extending transversely across, and underlying and in vertical alinement with the free
- end of the bottom element to engage and support the same against downward movement, said free end of the bottom element and the rotary element having complementary projections and cut-outs whereby in one position of the rotary element the bottom element is engaged with and held by the rotary element in closed position, and in a second position of the rotary element the projections and cut-outs, register to enable the bottom element to move to open position, means to actuate the rotary element, and means to hold the rotary element in its said first named position.
5. In a pickling device, a pickling basket having a pivoted bottom with a free end and having spaced extensions projecting outwardly from said end and in substantially the plane thereof, a substantially straight shaft underlying and vertically alined with the said free end and being directly engageable with the extensions to hold the bottom closed in one position of the shaft and having cut-outs for registry with the extensions whereby to allow the bottom to open in a second position of the shaft, means to rotate the shaft and means to limit rotation of the shaft upon movement thereof to the position wherein same holds the bottom closed.
6. In a pickling device, a pickling basket having a pivoted bottom with a free end, a shaft disposed adjacent to the bottom and having portions on which the under side of the free end of the bottom directly seat, means to rotate the shaft to move said portions out of alinement with the free end of the bottom to allow the latter to move downwardly to open position, and means to limit rotation of the shaft to hold same in bottom-supporting position.

STEPHEN L. WILLIAMS.
